UNITED STATES PATENT OFFICE.

ENOCH W. MORGAN, OF PHILADELPHIA, PENNSYLVANIA.

DYEING-MACHINE.

1,365,936.

Specification of Letters Patent. Patented Jan. 18, 1921.

Application filed October 11, 1920. Serial No. 416,168.

To all whom it may concern:

Be it known that I, ENOCH W. MORGAN, a citizen of the United States, residing at Philadelphia, in the county of Philadelphia 5 and State of Pennsylvania, have invented certain new and useful Improvements in Dyeing-Machines, of which the following is a specification.

This invention relates to machines for 10 treating textile goods and other articles with liquid, and more particularly with dyes; and it consists of a revoluble barrel which is revolved intermittently and in which the goods are brought into intimate and 15 repeated contact with the liquid as hereinafter fully described and claimed.

In the drawings, Figure 1 is a vertical longitudinal section through a machine constructed according to this invention. Fig. 2 20 is an end view of the machine, showing the preferred driving mechanism. Fig. 3 is a cross-section through the machine, taken on the line 3—3 in Fig. 1. Fig. 4 is a plan view showing a portion of one of the perforated 25 partitions.

A suitable supporting frame 4 is provided and 5 is a barrel provided with tubular trunnions 6 and 7 which are journaled in bearings 8 on the frame. This barrel is 30 shown as a straight cylindrical vessel, but it may be of any other approved form. The barrel is provided with a steam jacket 9, and steam to heat the liquid contents of the barrel is admitted to the jacket through 35 the trunnion 6, and is let out through the trunnion 7. The flow of steam and the drainage of condensed steam from the jacket is controlled and effected in any approved way.

40 The barrel is provided with a charging opening 10 on one side, and this opening is provided with a door or doors 12. Two doors are preferably provided, and they are preferably hinged to the steam jacket. 45 The charging opening 10 extends for the full length of the barrel, and is formed in a distance-piece 11 secured between the steam jacket and the barrel. Suitable stays 14 are also provided between the steam 50 jacket and the barrel.

Perforated partitions 15 are secured inside the barrel, and are arranged one on each side of the charging opening, so that a central chamber for the goods is provided, 55 between the chambers or spaces 16 for

liquid. The partitions 15 are provided with a multiplicity of small perforations 16' so that they form sprinklers, and openings 17 of relatively large area are formed at the end portions of the partitions. Plates 18 and 19 are arranged between the partitions, and these plates also preferably have a multiplicity of small perforations. These plates form passages 20 which together with the openings 17 permit a predetermined quantity of liquid to flow freely from one liquid space 16 to the other. The plate 18 is secured in the goods chamber of the barrel, and the plate 19 is secured removably to the barrel, so that it can be slid into and out 60 of place through the charging opening. The partitions 15 have also ribs 15' for retaining the dye.

The goods chamber of the barrel is provided with suitable supports 22 for the 75 goods. These supports have any suitable passages or openings for liquid, and they may be formed of bars, wire-work or other similar devices. The supports may be arranged horizontally or vertically, and the 80 horizontal supports may conveniently be shelves which are slidable in guides 24 on the ends of the barrel, and which are removable through the charging opening 10. The barrel may be used without the supports 22 if desired. When the supports are used, they are slid into the barrel, and the removable plate 19 is then secured in position.

The object of using the supports 22 is to 90 divide the goods to be treated into a number of separate parcels, so that they will not become matted together. The goods to be treated are placed in the barrel with the dye or other liquid. If the dye is to be heated, 95 steam is admitted to the barrel, and preferably before the goods are placed in it. For this purpose the barrel is provided with a steam pipe 26 which is connected to the steam inlet trunnion 6 and provided with 100 a suitable stop valve 27. Any desired quantity of dye can be placed in the barrel, and it is preferably filled to about the level of its axis.

The barrel is revolved intermittently by 105 any approved driving devices, intermittent toothed gearing being preferably used. An intermittent toothed pinion 28 is secured on one of the trunnions, and it gears into an intermittent toothed wheel 29 which is se- 110

cured on a driving shaft 30. The shaft 30 is journaled in bearings 31 on the frame, and is revolved by any approved motor. The wheel 29 has a toothless portion 32 on its periphery which engages with toothless portions or dwells 34 on the pinion 28. The dwells 34 are arranged to correspond with the perforated sprinkling partitions 15 of the barrel. The barrel is revolved constantly in the same direction.

When the barrel is in the position shown, the toothless portion 32 of the wheel 29 is in engagement with one of the dwells 34, so that the barrel is held stationary. The dye or other liquid descends by gravity into the lower part of the barrel. The passages 20 permit the liquid to descend freely, and their effective area may be adjusted in any approved way, as, for instance, by obstructing or closing some of the large openings 17 by any suitable valves or other similar devices, such as the slideable plate 23 shown in Fig. 4.

When the toothed part of the wheel 29 engages with the teeth of the pinion, the barrel is revolved rapidly for one-half a revolution. This raises a portion of the liquid to the upper side of the barrel. The toothless portion of the wheel then engages with the other dwell on the pinion, and, while the barrel is held stationary, the liquid is showered and sprayed onto the goods in the upper part of the barrel, and the goods in the lower part of the barrel are immersed in the liquid or dye. This operation is repeated until the goods have been sufficiently treated with the liquid. A pipe 36 is provided for admitting dye to the barrel and for drawing off or draining the dye out of the barrel, and the barrel is also provided with any other suitable accessories, such as a gage glass, and a thermometer, which are not shown.

The ribs 15' on the partitions 15 retain a predetermined quantity of the dye on the partitions so as to make an effective shower while the barrel is stationary.

What I claim is:

1. The combination, with a barrel provided with perforated partitions arranged on opposite sides of its axis and adapted to spray liquid onto the goods in the middle part of the barrel, of a steam heating device arranged around the said barrel, and means for revolving the barrel intermittently and holding it stationary while the liquid is being sprayed on the goods.

2. The combination, with a barrel provided with perforated partitions arranged on opposite sides of its axis, of a steam jacket secured around the barrel, tubular trunnions secured to the jacket and adapted to supply steam to the jacket, and means for revolving the barrel intermittently and holding it stationary while the liquid is being sprayed on the goods.

3. The combination, with a barrel provided with perforated partitions arranged on opposite sides of its axis, of a steam jacket secured around the barrel, tubular trunnions secured to the jacket and adapted to supply steam to the jacket, a steam pipe provided with a stop valve and adapted to admit steam from one of the trunnions to the interior of the barrel, and means for revolving the barrel intermittently and holding it stationary while the liquid is being sprayed on the goods.

4. The combination, with a barrel provided with perforated partitions arranged on opposite sides of its axis and adapted to spray goods in the middle part of the barrel, said barrel having also passages which permit a portion of the liquid to descend freely without passing through the goods, of means for revolving the barrel intermittently and holding it stationary while the liquid is being sprayed on the goods.

5. The combination, with a barrel provided with perforated partitions arranged on opposite sides of its axis and adapted to spray goods in the middle part of the barrel, of perforated spraying plates arranged between the said partitions and forming passages which permit a portion of the liquid to descend freely without passing through the goods, and means for revolving the barrel intermittently and holding it stationary while the liquid is being sprayed on the goods.

6. The combination, with a barrel provided with perforated partitions arranged on opposite sides of its axis and adapted to spray goods in the middle part of the barrel, said barrel having also passages which permit a portion of the liquid to descend freely without passing through the goods, said barrel having also an outlet door on one side and guides on its ends, of supports for the goods slideable in the said guides and removable through the said outlet door, and means for revolving the barrel intermittently and holding it stationary while the liquid is being sprayed on the goods.

7. The combination, with a barrel provided with perforated partitions arranged on opposite sides of its axis and adapted to spray goods in the middle part of the barrel, said barrel having also passages which permit a portion of the liquid to descend freely without passing through the goods, of supports which divide the middle part of the barrel between the said passages into compartments for holding the goods in separate parcels and permitting the liquid to pass through them, and means for revolving the barrel intermittently and holding it stationary while the liquid is being sprayed on the goods.

8. The combination, with a barrel provided with perforated partitions arranged

on opposite sides of its axis and adapted to spray goods in the middle part of the barrel, said barrel having also passages which permit a portion of the liquid to descend freely without passing through the goods, said barrel having also means for retaining portions of the liquid above the partitions while the

barrel is stationary, of means for revolving the barrel intermittently and holding it stationary while the liquid is being sprayed on the goods. 10

In testimony whereof I have affixed my signature.

ENOCH W. MORGAN.
